FLOOR WAXER

August M. Mazzarelli and Frank M. Mazzarelli,
New York, N. Y.

Application November 28, 1956, Serial No. 43,982

Term of patent 7 years

(Cl. D9—2)

FIG. 1

FIG. 2

FIG. 3

Fig. 1 is a side elevational view of a floor waxer, showing our new design, portions of the handle being broken away to indicate indeterminate length;

Fig. 2 is a front elevational view thereof with the upper end of the handle broken away for the convenience of illustration; and

Fig. 3 is a top plan view thereof as shown in Fig. 2.

We claim:

The ornamental design for a floor waxer, substantially as shown.
